Williams & Pritchard

UNITED STATES PATENT OFFICE.

HERBERT JOYCE, OF WASSAIC, NEW YORK, ASSIGNOR OF ONE-HALF TO FREDERICK G. ASHLEY, OF BROOKLYN, NEW YORK.

DIAPHRAGM.

Application filed December 13, 1922. Serial No. 606,566.

To all whom it may concern:

Be it known that I, HERBERT JOYCE, a subject of the King of Great Britain, and a resident of Wassaic, Dutchess County, State 5 of New York, have invented certain new and useful Improvements in Diaphragms, of which the following is a specification.

This invention relates to diaphragms for reproducing sound and is herein illustrated 10 as applied to the sound box of a well known form of phonograph, adapted to reproduce what are known as hill and dale records. According to the present invention, a suitable diaphragm base is coated with wax prefer- 15 ably out to the very edge of the mounting of the diaphragm, so that there is a continuous coating of wax over the entire area of the diaphragm which is exposed to the air. The diaphragm base upon which the coating is 20 applied is preferably a rigid, resilient sheet,—an ordinary mica diaphragm forms an excellent base for the purpose. In the form herein illustrated the wax is applied only to one side of the mica, the side remote from the 25 tone-arm or horn. It is found advantageous to apply two layers of wax; one fairly hard layer, such as paraffin wax of one of the higher melting points, and above that to apply a second wax coating of a softer wax 30 such as beeswax. Coatings of various thick- 35 nesses have been found useful and the most satisfactory coating has been found to be one in which the two layers are each slightly less than $\frac{1}{16}$ of an inch thick. Other fea- 40 tures and advantages will hereinafter appear:

In the accompanying drawings Fig. 1 is a rear view of a sound box showing the 45 coating of the diaphragm.

Fig. 2 is a sectional side view showing the rigid resilient base and the two layers of wax superposed thereon.

A mica sheet 1 forming a well known kind of diaphragm is held by a screw 2 to 45 the long arm 3, pivoted at 4, of the needle lever which carries on its other arm 5 a needle 6. The mica sheet 1 is held between two rubber gaskets 7 and 8 in any usual or desired manner, the gaskets supporting the 50 diaphragm on the opposite sides and being held against it by the usual body 9 and its turned over edge 10 which forms a supporting frame. The screw 2 is centrally located in the diaphragm opposite the opening 11,

which leads to the tone-arm (not shown). According to the present invention the mica or other sheet 1 is coated with a layer of paraffin wax 12, preferably by melting 122 to 124° melting point paraffin wax and pouring a suitable quantity while very liquid 60 upon the horizontal cold sheet 1, which may be at room temperature. Preferably the coating thus applied is somewhat less than $\frac{1}{16}$ of an inch thick. When this coating is thoroughly cold a similar coating 13 of beeswax is made upon the outside of the paraffin wax 12 by pouring upon it melted beeswax hot enough to flow freely so as to make a 65 layer of the same thickness, but not hot enough to melt away the underlying layer 70 of paraffin wax. When the coatings are cold the diaphragm is ready for use. If the coatings extend entirely up to the metal edge or margin 10 of the diaphragm mounting 75 and appear to adhere to the edge, it will be found that sound is reproduced practically 80 free from the scratching, which is ordinarily heard from sound records. The improvement in the reproduction is particularly noticeable in the clearer reproduction of the high notes.

Having thus described my invention, by way of example, what I claim and desire to secure by Letters Patent is:

1. An acoustic diaphragm having associated therewith layers of wax of different degrees of hardness.

2. An acoustic diaphragm having associated therewith layers of wax of different degrees of hardness, the wax of one layer being of lower melting point than the wax of the other of said layers.

3. An acoustic diaphragm having associated therewith a layer of wax upon which is superimposed a softer layer of wax.

4. An acoustic diaphragm having associated therewith a layer of wax upon which is superimposed a layer of wax the melting point of which is less than of the wax of the first mentioned layer.

5. An acoustic diaphragm having a layer of paraffin wax, and a layer of beeswax associated therewith.

6. An acoustic diaphragm having associated therewith a layer of paraffin wax upon which is superimposed a layer of beeswax.

7. The combination with a frame of an acoustic instrument, of a diaphragm having

attached to one side thereof a coating of wax, said wax being attached to said frame adjacent the periphery of said diaphragm.

8. The combination with a frame of an acoustic instrument, of a diaphragm having associated therewith layers of wax attached to said frame adjacent the periphery of said diaphragm.

9. The combination with a diaphragm

support, of an acoustic diaphragm supported by said support and having associated therewith a layer of paraffin wax and a layer of beeswax, said layers of wax being adhesively attached to said support adjacent the periphery of said diaphragm.

In testimony whereof, I have affixed my signature to this specification.

HERBERT JOYCE.
